UNITED STATES PATENT OFFICE.

HEINRICH NEUY, OF HAMBURG, GERMANY.

VEHICLE FOR RECEIVING AND TRANSPORTING REFUSE AND THE LIKE.

Application filed November 6, 1926, Serial No. 146,729, and in Germany November 10, 1925.

The vehicles for receiving and transporting refuse and the like have the disadvantage that they can receive a comparatively small quantity of material only when the loading edge is low and are difficult to load when the loading edge is high. A further disadvantage of vehicles of this kind in which a dust-proof opening is provided for filling in the material consists in this that underneath the filling places cones of the material are formed which make further filling difficult or impossible. These cones of material must then be spread either manually by poking in which case the filling of the vehicle cannot be carried out absolutely dust-proof or mechanically by means of racks, pushers or the like.

The object of the invention is to provide a process for loading or charging a vehicle with refuse and the like in which the container receiving the material has the form of a drum rotatably mounted upon the body of the vehicle and is provided with a lateral filling opening. According to the invention the refuse and like material is to be filled into the drum through the lateral filling opening to the height or level of the loading edge which is adjustable to any desired height whereupon by turning the drum to and fro and utilizing the weight of the material as well as the natural angle of inclination the material is brought to the side of the drum opposite the filling place and lifted above the height of filling.

In this manner it is possible to load the side of the drum opposite the loading side and to remove the cone formed underneath the loading place without poking or using racks, pushers or the like.

In the accompanying drawing a mode of carrying the process according to the invention into effect is shown diagrammatically in Figs. 1-4.

The drum shaped body 2 of the vehicle is rotatably arranged in known manner upon guide rolls or pivots 5 is loaded through opening 1 as shown in Fig. 1 as far as possible over the loading edge *a* which is adjustable to any desired height. The body of the vehicle is then rotated by means of a pinion 4 meshing with a ring gear 3 on the vehicle body in the direction of the arrow shown in Fig. 1 through an angle of about 180°. The material 6 filled into the body then comes by its own weight and by its natural angle of inclination into the position

shown in Fig. 2. Thereupon the body of the vehicle is brought back into its original position by turning said body in the direction of the arrow shown in Fig. 2. In consequence of its natural angle of inclination the material thereby comes about in the position shown in Fig. 3. The cone of material is therefore removed and the material itself is brought to the side of the drum opposite the loading edge so that further filling is possible without being rendered difficult by cones. The filling and rotating may be repeated as often as desired so that after two or three repetitions the body of the vehicle is loaded above the filling level as shown in Fig. 4.

The discharge of the drum is effected through the bottom in such a manner that the cover provided in the upper part of the drum shaped vehicle body and upon which during the running of the vehicle no strain is exerted is rotated downwardly and opened. Any other discharge, for instance, by hind tipper or crane tipper is, however, also possible in a simple manner.

The rotation of the drum may be effected mechanically in such a manner that the rotational movement in any desired adjustable extreme position of the vehicle body is automatically reversed and then automatically stopped in the original position, so that the rotating requires little time and work only. The sticking of the material to the wall of the body may be favoured, if necessary, by longitudinal struts fixed to the inner wall of the drum. The material may be freely filled in by means of a shovel, vessel or the like or dust-proof by means of any desired filling device.

What I claim is:

1. A method of loading materials into a vehicle of the type having a rotatably-mounted container and a filling opening therein, which comprises the repeated steps of loading the material into the container of the vehicle through the opening thereof until it reaches the edge of the opening; and rotating said container to flatten out and rearrange said material in the container for a further supply of material.

2. A method of loading materials into a vehicle of the type having a rotatably-mounted container and a filling opening therein, which comprises the repeated steps of loading the material into the container of the vehicle through the opening until the

material reaches the edge of the opening; and rotating said container through an angle of approximately 180° to flatten out and re-arrange the material in the container for a further supply of material.

3. A method of loading materials into a vehicle of the type having a rotatably-mounted container in the form of a drum and a filling opening therein, which comprises the repeated steps of loading the material into the container through the opening until it reaches the edge of the opening; and rotating the container through an angle of approximately 180° and returning it to its original position to flatten out and rearrange the material in the container for a further supply of material.

4. A method of loading materials into a vehicle of the type having a rotatably-mounted container in the form of a drum and a filling opening therein which consists in the step of adjusting the container so that the opening shall be arranged at the desired height and which comprises the repeated steps of loading the material into the container through the opening until it reaches the edge of the opening; and rotating the container through an angle of approximately 180° and returning it to its adjusted position to flatten out and re-arrange the material in the container for a further supply of material.

5. A method of loading materials into a vehicle of the type having a rotatably-mounted container and a filling opening therein, which comprises the repeated steps of loading the material into the container of

the vehicle through the opening thereof to form a cone-shaped pile of material, the top of which approximately reaches the loading edge of the opening; and rotating said container to flatten out and rearrange the pile in the container to remove the cone for a further supply of material.

6. A method of loading materials into a vehicle of the type having a rotatably-mounted container and a filling opening therein, which comprises the repeated steps of loading the material into the container of the vehicle through the opening thereof to form a cone-shaped pile of material; and rotating said container to flatten out the pile in the container to remove the cone and arrange the flattened material toward the side of the container opposite the opening and extending thereabove and to the top of the container.

7. A method of loading materials into a vehicle of the type having a rotatably-mounted container and a filling opening therein, which comprises the repeated steps of loading the material into the container of the vehicle through the opening thereof to form a cone-shaped pile of material reaching the loading edge of the opening and rotating said container until at first the pile in the container is flattened and then the flattened material is lifted toward the side of the container opposite the opening, in order to create room for receiving a further supply of material.

In testimony whereof I affix my signature.

HEINRICH NEUY.
